UNITED STATES PATENT OFFICE

110,831

DESIGN FOR A COMBINED LAMP AND HORN

William C. Crimmins, Marion, Ind., assignor to
Delta Electric Company, Marion, Ind., a corporation of Indiana

Application June 21, 1938, Serial No. 77,976

Term of patent 7 years

To all whom it may concern:

Be it known that I, William C. Crimmins, a citizen of the United States, residing at Marion, in the county of Grant and State of Indiana, have invented a new, original, and ornamental Design for a Combined Lamp and Horn, of which the following is a specification, reference being had to the accompanying drawing, forming a part thereof.

Fig. 1 is a top plan view of a combined lamp and horn showing my new design;

Fig. 2 is a side elevational view thereof;

Fig. 3 is a front elevational view thereof.

The ornamental design for a combined lamp and horn, substantially as shown.

WILLIAM C. CRIMMINS.
